(57) **CLAIM**

The ornamental design for an inset for visors, as shown and described.

DESCRIPTION

FIG. 1 is top view of our design for an inset for visors, in which the design is hidden;

FIG. 2 is a front view thereof, in which the design is hidden;

FIG. 3 is a back view thereof;

FIG. 4 is a left side view thereof, in which the design is hidden;

FIG. 5 is a right side view thereof, in which the design is hidden;

FIG. 6 is a bottom perspective view thereof; and,

FIG. 7 is a bottom view thereof.

The broken lines shown in the drawings show unclaimed subject matter only and form no part of the claimed design.

1 Claim, 4 Drawing Sheets
